FLEXIBLE BAND, CHAIN OR LINKAGE

Application filed February 15, 1929. Serial No. 340,227.

This invention relates to improvements in the construction and manufacture of flexible bands, chains or linkages for use as articles of jewelry such as bracelets, wrist-watch straps, necklaces, girdles or the like.

One object of the invention is to provide a band, chain or linkage comprising a series of articulated link-elements joined together in flexible relation to adapt the article to conform to the contour of the surface on which it is worn.

Another object of the invention is to provide a construction of the type specified wherein the articulated link-elements are flexibly connected by means enclosed therein so that the mechanical structure is concealed from view and protected from disorganization.

Another object of the invention is to provide a construction of the type specified having the articulated link-elements flexibly joined together without the use of pins, rivets, screws or the like, and without requiring soldering at the joints.

Another object of the invention is to provide an article of the type specified which may be constructed from sheet-metal parts struck up in dies and capable of being rapidly assembled without particular skill or expertness on the part of the workman and without the use of tools.

Another object of the invention is to provide a construction of the type specified in which the link-elements are assembled in articulated relation by simply inserting the connecting means therein, and wherein the connecting-members are automatically interengaged and interlocked to permanently hold the parts in coupled relation by means at the ends of the band, chain or linkage.

Another object of the invention is to provide a construction of the type specified in which the connecting-members are adapted to be unlocked to disconnect the links to provide for altering the length of the bracelet.

Another object of the invention is to provide an article of the type specified adapted for economical manufacture and having a stronger and more durable structure.

Further objects of the improvement are set

forth in the following specification which describes several preferred embodiments of the invention as illustrated by the accompanying drawings. In the drawings:

Fig. 1 is a perspective view illustrating the improved construction as embodied in a flexible band, chain or linkage adapted for use as a wrist-watch strap or bracelet;

Fig. 2 is a bottom plan view of a portion of the band or linkage showing certain of the link-elements in section to illustrate the arrangement of the interengaging connecting-members and the end element for locking them in place;

Fig. 3 is a similar view showing the method of inserting the connecting-members into the hollow link-elements;

Fig. 4 is an edge view of a section of the band, chain or linkage shown in Fig. 2;

Fig. 5 is a longitudinal sectional view of the end portion of the band, chain or linkage, taken on line 5—5 of Fig. 3;

Fig. 6 is a perspective view of one of the connecting-members;

Fig. 7 is a perspective view of the end-member or clasp employed for connecting the band to the bails of a wrist-watch or the like;

Fig. 8 is a plan view similar to Fig. 2 showing a modified form of construction of the article;

Fig. 9 is a sectional plan view showing a modified form of the locking means for holding the series of connecting-members in place in the links; and

Fig. 10 is a cross-sectional view of the same taken on line 10—10 of Fig. 9.

The present invention consists in general in providing a novel and improved construction of connecting-means for joining the link-elements of flexible bands, chains and linkages without the use of pins, rivets, screws or other mechanical parts of a like nature. In the present embodiment, the finished article consists in a flexible band, chain or linkage adapted for use as a wrist-watch strap or bracelet in accordance with a prevailing style, and also capable of being used for other purposes, for instance, as a necklace, arm-band, anklet, girdle, watch-guard

or similar article of jewelry and adornment.

As herein shown, the band or linkage is of the flat strap type comprising a series of relatively narrow hollow link-elements 2 extending transversely of the band and closely coupled together to permit flexure of the article as a whole. In other cases, however, the link-elements 2 may be of different outline and contour, for instance, of cylindrical shape instead of rectangular in cross-section. For producing a relatively flat strap or band the link-elements 2 are cut from lengths of tubular stock such as commonly used in jewelry manufacture; and as illustrated in the present drawings the links are in the form of relatively narrow open-ended boxes each having a flat top 3, a corresponding bottom 4, and narrower flat sides 5.

The connecting-means for the link-elements 2 are constructed in the form of relatively flat bifurcated members 6 of substantially hairpin shape. The members 6 may be punched out in dies from suitable sheet-metal stock and a pair of members are employed for each connection, one member being reversed in position with relation to the other when they are inserted into the link-elements 2. Each of the members 6 is formed with a pair of opposite legs 8 and 9, connected by an end-piece 7, and adapted to straddle the sides of two adjacent link-elements 2 when they are inserted into the opposite ends thereof as shown in Figs. 2 and 3. One leg 9 of the member 6 is made slightly longer than the other leg 8 and is provided at its end with a laterally projecting lug or abutment 10 adapted to interlock with the shorter leg 8 of the next connecting-member in the series. That is to say, as the members 6 are inserted into the opposite ends of the link-elements 2 in the manner as shown in Fig. 2 their lateral edges will abut and the lug 10 on the longer leg 9 of the first element will extend across and interlock with the end 45 of the short leg 8 on the next connecting-member in the series. When the connecting-members 6 are inserted in place in the link-elements 2 in this manner their end-pieces 7 will align in close relation along the marginal edges of the band or linkage as shown most clearly in Fig. 1. In other instances, however, the end-pieces 7 may be let into the ends of the link-elements 2 so that their edges will be flush with the marginal edges of the band as shown in Fig. 8 and hereinafter more particularly described.

In assembling the parts to form the band, chain or linkage, the tubular link-elements 2 are arranged side by side in series and the connecting-members 6 inserted into their ends with the abutments or lugs 10 on their longer legs 9 both on the same side and in opposed relation at the center. In this way a gap is left between the ends of the short legs 8 of the members 6 and the lugs on the

long legs 9 of the pair previously inserted project into this gap and interlock with the short legs of the next succeeding pair of members 6 in the series. It will therefore be observed that as the link-elements 2 are connected in assembled relation, starting at the left as viewed in Fig. 2, each pair of connecting-members 6 inserted will interlock with the previously inserted pair of members to hold them in place. When the parts of the band, chain or linkage have been assembled in this manner to obtain the required length, means are applied to lock the last applied or endmost members 6 in place, whereby all of the interlocking connecting-members will be held against withdrawal from the ends of the link-elements 2.

Any suitable means may be provided for permanently securing the endmost pair of connecting-members 6 in place and two different forms of construction are illustrated in the present drawings. As shown in Figs. 1 to 5, inclusive, the two opposite connecting-members 6 of the endmost pair are held in place by a loop-like strap or band 12 constructed of relatively thin sheet-metal and normally held in position enclosing a portion of the end-clasp or connector 15. The end-clasp or connector 15 may be of any suitable construction as usually employed for attaching the ends of the strap to the bails of the wrist-watch, or it may be in the form of a catch or clasp for fastening the free ends of the bracelet together.

As shown in Figs. 5 and 7, the end-member or clasp 15 is provided with a box-like portion 16 similar in form to the tubular link-elements 2. Preferably, the length of the box or, more properly, the width of the member 15, corresponds to the whole width of the strap or band, and its side wall 17 is cut away at the ends to provide notches or openings 18 for receiving the end-pieces 7 of the connecting-members 6, see Fig. 7. The opposite side of the box may be left open and the metal from the top strip 19 extended in a hook 20 of substantially cylindrical shape in cross-section. The hook 20 may be used as a clasp, or in other cases it may receive the cylindrical barrel 21 of a cross-member having pins or pintles 22 at its ends which snap into holes in the lugs or projections on the sides of the watch as is a usual practice. The barrel 21 of the cross-member contains a spring 23 which bears against the enlarged ends of the pintles 22, thereby tending to force them outwardly from the sides of the clasp as shown in Fig. 2. In attaching the end-member 15 to the watch the pintles are pressed inwardly through the use of a knife-blade or some other sharp instrument to telescope them within the barrel 21 whereby they may be snapped into the holes in the lugs on the wrist-watch.

The narrow strap or band 12 previously

referred to, fits around the hollow box-portion 16 of the clasp or end-member 15 with its ends abutting the ends of the two last connecting-members 6 of the series as 5 illustrated most clearly in Figs. 1 and 2. Preferably, the ends of the strap member 12 are punched or indented to form round protuberances 24 on the inside, these protuberances being adapted to engage over the sides 10 of the two endmost connecting-members 6 as shown in Fig. 2, thereby holding the strap in place against the shoulders 25 at the ends of the hook 20, see Figs. 3 and 7. As an additional precaution, one side of the strap 15 12 may also be punched or indented to form a protuberance 26 which snaps into a hole 27 on the top strip 19 of the box portion 16 of the connector 15.

The locking-element or fastening-means 20 for the connecting-members as above described may be employed as a manually-adjustable device for releasing the connecting-members 6 when it is desired to disassemble the parts of the band for the purpose of altering 25 its length. That is to say, this form of construction provides for uncoupling the end-members from the strap, band or linkage whereby one or more of the link-elements may be taken out to shorten the bracelet or 30 others added to increase its length. To provide for this adjustment in the length of the bracelet the locking-element 12 is slid back into the position as illustrated in Fig. 3 so that the last pair of connecting-members 6 35 may be withdrawn from the end link 2. After the end-member 15 has been disconnected additional link-elements 2 may be inserted and the endmost one again connected to the clasp, or in other instances the locking-element 12 40 may be slid back far enough to remove one or more of the link-elements 2. It will be understood that when the element 12 is slid back on the band its protuberances 24 will spring up over the ends of the connecting- 45 members 6 and its other projection 26 will be released from the hole 27; and when the locking-element 12 is slid back into place again to encompass the hollow portion of the clasp 15 the protuberances 24 and 26 will again 50 snap into position to act as detents to hold the connecting-members 6 in place.

Fig. 8 of the drawings illustrates a modified form of construction in which the tubular link-elements 30 are of greater length to 55 provide a wider strap, band or bracelet, and wherein the ends of the connecting-members 6 are arranged flush with the ends of the links. To provide for this the side walls 31 of the link-elements 30 are cut away at their ends 60 to adapt them to receive the end-pieces 7 of the connecting-members 6. It will also be noted from this view that the opposite connecting-members 6 do not meet at the center. That is to say, they are shorter in proportion 65 to the length of the tubular link-elements 30,

but nevertheless one element interlocks with the next one in the series in the same manner as where the ends of the long legs 9 of the connecting-members 6 abut as shown in Fig. 2. The same form of locking-element for 70 the connecting-members 6 may be employed with this type of construction.

Figs. 9 and 10 of the drawings illustrate a modified form of construction of the locking-means for holding the connecting-members 75 6 in place. In this modification the end-member or connector 32 has its sides cut away to form strips of metal 33 which are bent around to enclose and hold together the lateral lugs 10 on the last pair of connecting-members 6 in the series. In this manner, the connecting-members 6 of the endmost pair are locked or anchored in position whereby 80 they, in turn, will act against the lugs 10 in the next adjacent pair of connecting-members, and so on throughout the series so that 85 all of the connecting-members are held in place by the anchoring of the endmost pair.

It will be observed from the foregoing that the present invention provides a novel 90 and ingenious construction for flexibly connecting the links of a strap, band, bracelet or the like. No pins, rivets, screws or other like mechanical elements are employed in the structure, the connecting-means being 95 simply flat pieces of sheet-metal which may be stamped out at very economical cost. The link-elements themselves are simple in form and structure and may be manufactured from tubular stock with no forming or other tool 100 operations required.

In assembling the parts of the band, chain or linkage it is only necessary to bring the tubular or hollow links into close association and then insert the connecting-members 105 into their ends to cause them to interengage whereby the last pair of connecting-members hold the previously inserted ones in place. The interengaging legs of the connecting-members hold the links in close association while adapting them to rock or cant, one with respect to another, to provide for flexure of the articulated structure, and the parts may be permanently joined together by a locking or anchoring means at 110 the end. It will thus be observed that no soldering is necessary and no skillful hand-work is required, such as bending or forming the parts with pliers or other tools.

By employing a single means to anchor the 115 end connecting-members, whereby all of these elements are held in place, the manual disconnection of the links is made more convenient so that the novice may disconnect the parts to shorten the bracelet or to insert 120 additional links to increase its length.

The improved structure is particularly 125 strong and durable in use, with the interengaging connecting-members tending one to reinforce another, and the finished ar- 130

ticle is more artistic in appearance than similar devices of the prior art since its mechanical structure is entirely covered and hidden from view.

5. It has been noted that the form of the link-elements may be changed without reference to the structure and arrangement of the connecting-members. Various modifications may also be made in the form and 10 construction of the connecting-members without departing from the spirit or scope of the invention and, therefore, without limiting myself in this respect, I claim:

1. In a band, chain or linkage, the combination of a plurality of link-elements, 15 means for connecting said elements in articulated relation comprising bifurcated members inserted into adjoining links in straddled relation with portions thereof, said connecting-members each having means engaging 20 with the next connecting-member in the series, and means for locking certain of the connecting-members in place whereby said members act one against another to hold the 25 whole series of said members from withdrawal.

2. In a band, chain or linkage, the combination of adjacent link-elements having 20 hollow portions, and means for connecting a plurality of said elements in articulated 30 relation comprising bifurcated members adapted for insertion into the hollow portions of two adjoining links to straddle the opposite walls thereof, said connecting-members 35 each having a portion adapted to engage with the next connecting-member in the series, and means at the end of the linkage for locking the last pair of connecting-members in place whereby each pair of connecting-members acts on the next pair in the 40 series to hold them from withdrawal.

3. In a band, chain or linkage, the combination of a plurality of link-elements arranged in series, bifurcated connecting-members 45 arranged in straddled relation with respect to portions of adjoining links to connect them together, said bifurcated members interengaging one with another, and means for fastening the endmost connecting-members 50 in position whereby said members act one against another to retain the whole series of said members in place.

4. An improved construction of band, chain or linkage comprising a plurality of link-elements arranged in series with portions thereof in adjoining relation, and a series of complementary connecting-members of bifurcated form each straddling the adjoining 60 portions of two link-elements to connect them together and arranged with one connecting-member interengaging with the next member of the series, and means for securing the end member of the series in position whereby said members act one against another to retain 65 all of the connecting-members in place.

5. In a band, chain or linkage, the combination of a plurality of link-elements arranged in series, bifurcated connecting-members arranged to straddle portions of each two adjoining link-elements and interengaging one with another, clasping means at the end of the linkage, and means on the clasp engaging opposite portions of the endmost connecting-members to lock them together whereby the several members act one against another to retain all of said members of the series in place.

6. In a band, chain or linkage, the combination of a plurality of link-elements arranged in series, a series of bifurcated members arranged to straddle portions of adjoining link-elements to couple them together and interengaging one with another throughout the series, and locking-means engaging the endmost pair of connecting-members to hold them in position whereby said members act one against another to retain all of the members in place, said locking-means being manually operable to release the connecting-members to permit disconnection of the link-elements.

7. In a device of the type specified, the combination of a plurality of link-elements arranged in series, bifurcated members engaging opposite portions of adjoining link-elements to couple them together and arranged in interengagement one member with another, an end-member at the end of the band, means on said end-member engaging the endmost pair of connecting-members to lock them in position whereby said members act one against another to retain all of the connecting-members in place, said means adapted to be moved to release the connecting-members to permit disconnection of the parts, and yieldable detent-means for holding the locking-means in place.

8. A flexible metal strap comprising a series of relatively wide short links, a series of connecting elements inserted into said links from either side thereof, each element being provided with a projecting tooth adapted to enter an adjacent link, said element being retained in its link by the tooth of the element in the adjacent link, and means for retaining the last element in place.

In testimony whereof I hereunto affix my signature.

CHARLES H. KESTENMAN.
